UNITED STATES PATENT OFFICE.

SAMUEL R. PARKS, OF PAWTUCKET, RHODE ISLAND.

OIL-CAN.

No. 870,684.

Specification of Letters Patent.

Patented Nov. 12, 1907.

Application filed February 6, 1907. Serial No. 356,118.

To all whom it may concern:

Be it known that I, SAMUEL R. PARKS, a citizen of the United States, residing at Pawtucket, in the county of Providence and State of Rhode Island, have 5 invented certain new and useful Improvements in Oil-Cans, of which the following is a specification.

My invention relates to improvements in oil cans and the purpose of my invention is to provide an oil can having a self cleaning plunger for the purpose of 10 removing obstructions from the nozzle and having also a device for causing the bottom of the can to return to its normal condition after pressure thereon has been removed. I accomplish these objects by the mechanism shown in the accompanying drawing showing 15 a central vertical sectional view of an oil can constructed in accordance with my invention, and in which

a represents the body proper of the oil can, a' its nozzle and a² the orifice of the nozzle; a³ designates the flexible bottom of the can. Secured to this bottom 20 is a metallic strip e of brass or steel or some other elastic metal; e is a similar metallic member also secured to the bottom a³.

e and e are ordinarily attached to the bottom a³ by the rivets d but may be secured in any other suitable 25 manner. The member e is curved upward at its free extremity and bears lightly on the under surface of the member e when the can is not in use.

Pivoted on e by an ordinary hinge joint b' is the plunger b, consisting of a metallic rod of steel, brass or 30 some comparatively rigid metal. Normally the plunger b reaches just to the orifice of a² or remains a trifle within the same, but when pressure is exerted on the bottom a³, through the agency of the members e and e the plunger b is projected even with or a little outside 35 of the orifice a² as shown by the dotted lines b². The plunger thus operates to clear the orifice or nozzle from any obstruction that may accidentally clog it. The plunger b is made enough smaller than the orifice a² to allow of a free flow of oil even when b is in the 40 position shown by the dotted lines.

When the pressure is removed from the bottom a³, the latter is aided in its return to its normal position by the pressure of the two spring members e and e. It is a common defect of oil cans of the character dis-

closed to have the bottom a³ remain projecting upward 45 after the pressure is removed so that it becomes almost impossible even when the nozzle is clear to force the oil out of the nozzle, the only way in which this can be accomplished being by unscrewing the nozzle altogether and introducing some tool into the body of the 50 can and pushing the bottom a³ downward to its normal position. But by means of the members e and e the tendency to remain upward is entirely removed and the bottom a³ is always in condition for the forcing of 55 the oil out through the nozzle by the application of pressure on the bottom.

I am aware that prior to my invention oil cans have been in use and patents have been granted therefor which embody a plunger operating in the nozzle of the can. I am not aware however, that any such device 60 has been used in combination with the supplementary springs e-e for the purpose of restoring the flexible bottom of the can to its normal position on removal of the pressure therefrom.

I do not therefore broadly claim an oil can having a 65 plunger adapted to work in the nozzle thereof for the purpose of freeing the same from obstructions, but

What I do claim and desire to secure by Letters Patent is

1. In an oil can, a receptacle having a nozzle, a flat 70 spring member secured adjacent one end to the inner face of the bottom of said receptacle and having its free end curved upwardly, a second spring member having one end secured to the inner face of the bottom of said receptacle adjacent the free end of the first mentioned spring member, said second spring member being curved to over-lie the free end of the first spring member and be engaged thereby, and a plunger rod extending into the nozzle and having its lower end pivoted to the free end of said second spring member. 75

2. In an oil can, a receptacle having a nozzle, two leaf-spring members secured to the inner face of the bottom of 80 said receptacle, one of said spring members over-lying the other spring member and engaging the free end thereof, and a plunger rod extending into the nozzle and pivoted at 85 its lower end to said over-lying spring member.

In testimony whereof I affix my signature in presence of two witnesses.

SAMUEL R. PARKS.
